13 Claims. (Cl. 62—193)

ABSTRACT OF THE DISCLOSURE

A refrigeration system is disclosed in the form of a liquid chiller. The compressor is of the screw type, and a stream of compressed gas and oil mist is used to cool the compressor and the motor. Variations in load are accommodated by an unloader on the compressor.

Specification

This invention relates to refrigeration, and more in particular to a refrigeration system and method wherein the compressor is of the screw type and the evaporator is in the form of a liquid chiller.

An object of this invention is to provide an improved refrigeration system. Another object is to provide an improved method and means for operating compressors of the screw type. Another object is to provide improved means for maintaining desirable operating conditions in a screw compressor under varying loads and extreme conditions of use. A further object is to provide for the above in a manner which avoids the difficulties which have been encountered in the past with similar constructions. These and other objects will be in part obvious and in part pointed out below.

In the drawings:

FIGURE 1 is a schematic representation of one embodiment of the invention; and,

FIGURE 2 is an enlarged vertical section of the lower left-hand portion of the evaporator-chiller shown at the bottom of FIGURE 1.

Referring to FIGURE 1 of the drawings, a refrigeration system 2 includes: a screw compressor 4 having an unloader 5 and driven by an electric motor 6; an oil separator 8; a refrigerant discharge line 10; a water-cooled condenser 12; a liquid refrigerant line 14 extending to a heat exchanger 16 which acts as a superheater unit; a liquid refrigerant dryer-filter 18; a liquid supply control assembly 20 through which the liquid refrigerant flows to a distributor header 22 for a plurality of liquid distributor tubes 24; an evaporator-chiller 26 having a refrigerant inlet header 28 and a refrigerant outlet tube plate 30; and, a gas refrigerant return line 32 through which the gas refrigerant returns to compressor 4.

The system also includes an oil circulating system including the following in series: an oil sump 34; an oil pump 36 driven by an electric motor 37; an oil cooler 38 through which water flows from a water inlet 40 to a water outlet 42 and which cools the oil flowing from the pump; and, an oil filter 44. An oil supply line 46 delivers oil under controlled pressure through distributor lines 48 to the motor bearings 50 and through lines 52 and 54 and 56 to compressor 4. Oil is also delivered from line 46 through a line 58 to the unloader 5, and through a line 59 to a load control unit 60.

During operation, the dense high-pressure oil-gas mixture is discharged from compressor 4 into a chamber 62 and thence through the motor where it is discharged axially against a baffle 64. This gas-oil mixture uniformly blankets and cools the stator and rotor of the motor,

2

and the motor also serves as a first-stage oil separator and removes, by centrifugal action, the bulk of the oil entrained in the gas. It has been found that something of the order of 95% of the oil is removed by the motor, and the oil accumulates at 66 in the bottom of the housing from which it flows through a line 35 to oil sump 34. The remaining fine oil mist is then separated from the gas by the action of baffle 64 and oil separator 8.

The disk-like baffle 64 deflects the stream of gas radially outwardly toward the outer wall and the oil then flows axially past the edge of the baffle through a passageway 68. Positioned in axial alignment with passageway 58 is an annular separator unit 70 which effectively removes the oil from the gas passing through it. Unit 70 is a loosely-formed ring of woven metal mesh which is wound upon a perforated tubular mandrel 72. Mandrel 72 forms a central gas discharge passageway 74 through which the gas flows to a gas discharge tube 73 and thence past a check valve 75 to line 10.

Unit 70 is spaced axially from baffle 64 so as to provide a radial passageway 76 through which the gas is free to flow radially inwardly to passageway 74 without passing through unit 70. Hence, the gas flowing axially through passageway 68 may proceed in the axial direction and flow into and through unit 70, or it may flow radially inwardly through passageway 76 without restriction into the central passageway 74. However, there is a tendency for there to be two-phase fluid flow, with the heavier mixture of gas and oil mist flowing along the outer casing wall and with the oil-free gas flowing adjacent the outer edge of baffle 64. Hence, as the stream flows past baffle 64, the oil-laden gas impinges against and enters unit 70, whereas the lighter oil-free gas makes the sharp turn around the edge of the baffle and flows radially inwardly through passageway 76 to passageway 74. The gas and oil mist entering unit 70 are slowed down, and the free gas migrates radially inwardly to passageway 74.

The oil from unit 70 adheres to the exposed surfaces of the wire mesh and flows downwardly and it collects at the bottom of unit 70 in the body of oil 66. It then flows to sump 34 through line 35. During operation there may be a tendency for the oil to bridge some of the passageways between the adjacent mesh portions in unit 70. Such bridging of the passageways could be expected to cause the oil to be re-entrained in the gas so as to reduce the effectiveness of the oil separator. However, with the present arrangement which permits the oil-free gas to flow freely through passageway 76, such re-entrainment does not occur, apparently because of the reduced gas velocity within unit 70. Also, the gas is readily diverted around any "plugged" passageways or portions without building up back pressure. At light loads there is a tendency for a high percentage of the refrigerant gas to flow through unit 70, whereas at increased loads an increased amount of the gas is free of oil and passes radially inwardly through passageway 68. The concentric discharge tube 73 insures that only oil-free gas flows to line 10.

It has been indicated above that the liquid refrigerant is delivered through distributor tubes 24 to the inlet header 28 of the evaporator-chiller 26. Chiller 26 has refrigerant tubes 80 which are supported within the shell between their ends and are mounted at their ends in tube plates 82 and 84, respectively (see also FIGURE 2). Mounted upon tube plate 82 is an orifice plate 86 which is held in place beneath a header 88. Orifice plate 86 has a plurality of small round openings or orifices 90 which are so positioned that one of them is in axial alignment with the end of each of the evaporator tubes 80. Header 88 has a plurality of ribs 92 which rest against orifice plate 86 and divide the area of the orifice plate into a number of header

chambers 94, each of which received liquid refrigerant through one of the distributor tubes 24. The pattern of ribs 92 is such that substantially the same number of orifices 90 is in each of the header chambers 94. Hence, the refrigerant supplied to each of tubes 24 is delivered through one of the headers and its orifices 90 to a specific group of evaporator tubes 80. Each of the orifices 90 acts as an expansion unit to provide the desired pressure drop, so that each of the evaporator tubes is in effect a separate evaporator. Also, substantially the same amount of the refrigerant flows to each chamber 94, and it is then distributed substantially evenly to a relatively small number of evaporator tubes. Hence, a highly efficient and dependable arrangement is provided for distributing the refrigerant substantially equally to all of the evaporator tubes.

As indicated above, the discharge ends of the evaporator tubes are supported in a tube plate 84, and the tubes open into the shell 96 of the heat exchanger 16. Water or other liquid to be cooled flows to and from shell 98 through a pair of lines 100 and 102. The refrigerant gas flowing through shell 96 of heat exchanger 16 cools the liquid refrigerant in coil 104, and the gas then flows through a filter 106 and through line 32 back to compressor 4. Positioned in the path of the returning refrigerant gas are two control bulbs 108 and 110 which control liquid supply or regulator valves 112 and 114, respectively through controllers 116 and 118. Valves 112 and 114 are in parallel. Valve 114 is fully closed at low loads, for example, below 35% of full load, and valve 112 determines the supply of liquid refrigerant to header 22 below 35% of full load. At loads above 35% of full load valve 112 is fully open and the control is exerted by valve 114.

As indicated above, unloader 5 controls the operation of the compressor so that it compresses the amount of refrigerant required for the load at all times. Accordingly, compressor 4 has a capacity control slide valve 120 which is shown in the full-load position wherein it forms a portion of the compressor-rotor casing 122. Slide valve 120 is mounted to slide to the left from the position shown to thereby expose an opening in the bottom of the rotor casing through which the suction gas can pass back from the central portion of the compressor to the suction inlet. In this way the amount of gas pumped is reduced.

Sliding valve 120 is connected through an operated spindle 124 to a piston 126 which is slideable in a cylinder 128. Piston 126 is moved to the left from the position shown by supplying oil at a controlled pressure to the chamber 130 in the cylinder at the right of the piston. Cylinder 128 is open at its left-hand end to the suction pressure of the compressor, but the sliding valve 120 is exposed to the pressure of the compressed refrigerant at the discharge side of the compressor. Therefore, when the compressor is operating the sliding valve 120 is urged toward the fully loaded position against the action of the oil under pressure in chamber 130. Hence, when oil is supplied to chamber 130 at a pressure greater than the discharge pressure, piston 126 is moved to the left; and, when the pressure of the oil in chamber 130 is less than the discharge pressure, piston 126 moves to the right. Oil supply line 58 is connected to chamber 130 through a shut-off valve 132 and a line 134. Hence, when valve 132 is open the oil at the full pressure in lines 46 and 58 is supplied at once to chamber 130. Also, a flow circuit is provided in parallel with valve 132 by line 59 and a restrictor valve 136 and a shut-off valve 138. Hence, when valve 132 is closed and valve 138 is opened, the oil at the pressure of line 46 flows through line 59, restrictor 136, valve 138 and line 134 to chamber 130. However, restrictor 136 limits the rate of flow so that piston 126 is moved at a reduced but controlled rate, whereas when valve 132 is open the piston moves at a rapid rate. This permits unloading rapidly by opening valve 132, or unloading at a slower rate by opening valve 138.

An additional control circuit is provided by a shut-off

valve 140 and a restrictor 142 in a line 144 which extends between the suction inlet of the compressor housing and chamber 130. Hence, when valve 140 is open the oil in chamber 130 is free to flow through line 134, restrictor 142, line 144, and valve 140 to the compressor casing. As indicated above, when the compressor is operating, the pressure of the compressed gas at the discharge side of the compressor urges sliding valve 120 toward its full-load position. Hence, when valve 140 is open, the pressure equalizes on the two sides of the piston because of the flow of oil from chamber 130, and the discharge pressure acting on slide valve 120 moves the slide and piston 126 back to the position shown. Restrictor 142 controls the rate of flow of oil from chamber 130 and therefore controls the rate of movement of the piston from a partial-load position to the full-load position.

The oil pressure in line 46 is controlled by a control unit 146 which has a valve 148 in a line 150 extending from line 46 to sump 34. A control line 152 extends from unit 146 to the discharge chamber 162 of the compressor so that unit 146 is responsive to the compressor discharge pressure. Unit 146 and its valve 148 act as a relief valve to maintain a pressure in line 146 which is a predetermined amount above the pressure in chamber 62. Illustratively, when the compressed gas pressure in chamber 62 is 200 pounds per square inch, the pressure in line 46 is 240 pounds per square inch. Hence, the oil delivered to the compressor through the various lines 48, 52, 54 and 56, and through lines 58 and 59 to the unloader is maintained at a predetermined value above the compressor discharge pressure. This insures a proper and adequate supply of oil to the motor bearings and to the compressor. It also insures that the unloader will operate properly. The opening of valve 132 when the compressor is partially or fully loaded will unload it at a rapid rate. The opening of valve 140 when the compressor is partially or completely unloaded will fully load it at a controlled rate.

It has been pointed out above that the heavy mixture of compressed gas and oil mist provides very satisfactory cooling of the motor. The oil mist produces a scrubbing action which improves the heat exchange factor and increases the cooling of the motor. The oil which is supplied to the compressor may contain some refrigerant and that refrigerant tends to flash and to aid in the cooling effect of the oil. It is thus seen that the refrigerant and the oil are circulated through separate cycles, but the inter-relationship is maintained which provides an improved mode of operation. Pump 36 is started prior to the starting of motor 6 so that the oil pressure builds up and provides oil for the motor and compressor, and the desired oil pressure is provided for the unloader. The controls also provide automatic unloading at start-up.

A hot gas bypass line 11 is connected between the gas refrigerant discharge line 10 and the liquid supply line 21 through which liquid refrigerant flows from valves 112 and 114 to distributor header 22. Line 11 includes a cut-off valve 23 and a restrictor 15. When desirable, valve 23 is opened to supply hot gas under the control of restrictor 15 to prevent stratification of the liquid phase and unstable operation of the refrigerant controls.

The invention contemplates that some of the evaporator tubes 80 may be supplied with more refrigerant than others. Such arrangements permit variations in the heat transfer or cooling effect in various zones. Accordingly, the orifices 90 may be of different sizes in any chamber 94 and from one chamber to another. Also, various of the chambers may have different numbers of tubes connected to them, with or without variations in the orifice size. Hence, great freedom of design is provided while permitting dependable and accurately controlled operation.

The system of FIGURE 1 includes standard components and controls. It is also understood that the embodiment herein disclosed is illustrative, and it is contemplated that

changes and modifications may be made within the scope of the invention.

What is claimed is:

1. In a refrigeration system, the combination of, a compressor having an unloader means and connector means by which it is moved between a fully-loaded position and fully-unloaded position, a cylinder and piston assembly operatively connected to said connector means to move said unloader means throughout its operating range, said compressor and unloader means including means utilizing force produced by compressed gas on the discharge side of the compressor to move said unloader means toward the fully-loaded position against the unloading action of said cylinder and piston assembly, an oil supply means, control means for said cylinder and piston assembly including means providing two parallel flow paths for oil flowing from said oil supply means to one end of the cylinder of said cylinder and piston assembly, one of said flow paths providing for the free flow of oil and the other of said flow paths including restrictor means providing for the restricted flow of oil to said one end of said cylinder thereby to produce a force acting through said connector means and urging said unloader means toward the fully-unloaded position, said control means also including means providing for the restricted flow of oil from one end of said cylinder to the other, thereby to equalize the pressures on the opposite sides of said piston within said cylinder and permit the force produced by the compressed gas to move said unloader means to the fully-loaded position, said control means including valve means to control the flow of oil along each of said flow paths.

2. Apparatus as described in claim 1 wherein said compressor is a screw-type compressor and wherein said unloader means comprises an unloader sliding valve and wherein said connector means comprises a spindle connected at one end to said piston and at the other end to said sliding valve, and wherein said one end of said cylinder is closed and the other end is open to the suction inlet for refrigerant gas being compressed by the compressor.

3. The combination as described in claim 1 which includes, an electric motor connected directly to said compressor, and a common casing enclosing said compressor and said motor with said compressor positioned to discharge a mixture of compressed gas and oil mist through said motor, and wherein said oil supply system includes an oil pump and an oil cooler which cools the oil flowing to said compressor.

4. The combination as described in claim 3 wherein said motor separates a substantial portion of the oil from the refrigerant, and which includes an oil separator positioned in axial alignment with the path of gas flow from said motor and including a central baffle which deflects the gas radially outwardly to an axially directed flow path, said oil separator also including an annular separator unit positioned in alignment with said annular flow path whereby the gas impinges against said separator unit, said separator unit being spaced from said baffle upon the opposite side of said motor to provide a free flow path radially inwardly between said separator unit and said baffle and then axially through said unit.

5. The combination as described in claim 4 which includes, means to direct oil from said motor and said separator unit to said oil supply system.

6. The combination as described in claim 5 which includes, a condenser and an evaporator, said evaporator being a chiller of the shell and tube type and having a plurality of refrigerant distributor circuits to supply refrigerant to said evaporator.

7. In a system of the character described, the combination of, a screw-type compressor having an unloader slide which is moved from and to a full-load position to control the operating capacity, operating means to move said unloader slide throughout its operating range and comprising a cylinder and piston assembly operatively con-

nected to said unloader slide, oil supply means to cool and lubricate said compressor and to provide oil under pressure to operate said cylinder and piston assembly, and control means to control the supplying of oil to said cylinder and piston assembly including a first valve which is opened to move said unloader slide to its fully-unloaded position and a second valve which is opened to provide a fluid flow path from one end to the other of the cylinder of said cylinder and piston assembly.

8. The combination as described in claim 7 wherein a fluid connection is provided between said cylinder and the inlet side of said compressor and said unloader slide is subject to the discharge pressure of said compressor, and which includes means forming a fluid flow path in parallel with said first valve and having a third valve and restrictor means therein, and wherein either said first valve or said third valve may be opened to supply oil to move said unloader valve toward its fully-unloaded position.

9. A system as described in claim 7 which includes, an electric motor connected to drive said compressor and positioned in the path along which the compressed gas and oil are discharged from said compressor, a shell construction enclosing said compressor and said motor and including means forming a passageway through which the compressed gas flows from said compressor and through said motor, and means to deliver oil from said oil supply means to the inlet of said compressor in sufficient quantity to cool the compressor and the refrigerant.

10. In a refrigeration system, the combination of, a screw-type compressor having an unloader slide which is moved to and from a full-load position to control the compressing of refrigerant, said unloader slide being urged to its full-load position by the action of the compressed refrigerant, a cylinder and piston assembly operatively connected to move said unloader slide away from said full-load position under the action of fluid supplied to said cylinder, and oil supply means connected to circulate oil through said compressor and also connected to supply oil under pressure to said cylinder, to move said unloader slide away from said full-load position.

11. In a refrigeration system, the combination of, an electric motor, a compressor connected to said motor and operative to compress the refrigerant in the system, a shell construction enclosing said motor and said compressor and including means forming a passageway through which the compressed refrigerant flows directly from said compressor through said motor, means constituting a continuous supply of oil, means to deliver oil from said supply to said compressor with the refrigerant which is being compressed, means to cool said oil prior to passing to said compressor to a temperature which is sufficiently low to permit said motor to be cooled by the refrigerant and accompanying oil flowing therethrough, and means to return the oil passing from said motor to said means constituting a supply of oil.

12. The combination described in claim 11 wherein said compressor is of the screw type and wherein the motor acts as an oil separator to separate a substantial portion of the oil from the compressed refrigerant.

13. The combination as described in claim 12 wherein the compressed gas is delivered axially against said motor accompanied by oil mist, and an oil separator to which the refrigerant is delivered after passing through said motor.
